[57] ABSTRACT

An improvement which permits automatic compensation for longitudinal workpiece expansion in a resistance heating apparatus of the type wherein a workpiece is transversely gripped between two pairs of spaced apart resistance heating contacts during heating. The improvement comprises mounting one of the pairs of contacts in a manner to be transversely movable relative to the other pair of contacts in a direction generally axial to the workpiece as it expands longitudinally during heating. Force means are provided for the movable pair of contacts for selectively axially moving the contacts to the initial position following heating of a workpiece in preparation for heating another workpiece.

WORKPIECE EXPANSION COMPENSATOR FOR RESISTANCE HEATING APPARATUS

This application pertains to the art of resistance heating and more particularly to resistance heating apparatus for elongated workpieces.

The invention is particularly applicable for use as a workpiece expansion compensator in resistance heating apparatus used for heating elongated generally cylindrical workpieces such as for example, steel shafts, and will be described with particular reference thereto; however, it will be appreciated that the invention has broader applications and may be used in other instances where it is desired to employ resistance type heating to elongated workpieces having any cross sectional configuration.

Heretofore, resistance heating apparatus which have been employed for resistance heating elongated workpieces have been comprised of two spaced apart pairs of resistance heating contacts wherein at least one of the contacts in each pair was movable toward and away from its associated contact. In operation, a workpiece was first placed between the pairs of contacts in a desired spaced relationship therewith and the movable contacts directed toward their associated contacts so as to clamp the workpiece therebetween. A heating current was then applied to the workpiece through the heating contacts by means of an outside current supply source. Following heating, the movable contacts were retracted to facilitate removal of the heated workpiece and insertion of a new unheated workpiece.

During heating, particularly to the elevated temperatures often incurred during the heat treating of elongated steel shafts, an elongated workpiece experiences a certain amount of longitudinal expansion. It was therefore necessary, in order to prevent damage to the workpiece or to the heating apparatus, to provide means for compensating for this longitudinal expansion as it occurred. In the prior types of apparatus, this has been accomplished by mounting the contact pairs so as to permit slight transverse movement of each pair relative to the other. However, in using these means, the contact pairs were continuously biased toward each other and to a "home" position by biasing means which oftentimes comprised spring members. Thus, as a workpiece was heated, the force exerted by the workpiece against the contact pairs during longitudinal expansion necessarily was required to overcome the force exerted in the opposite direction by the biasing means.

This prior type of longitudinal expansion compensator had two principal drawbacks. First, it was necessary for both contact pairs to move relative to each other such that any mechanical difficulty with one of the biasing means could affect the overall compensating ability of the apparatus to the extent that the desired and/or necessary longitudinal expansion compensation could not be realized and the entire heating apparatus would be damaged. Second, and as these compensators continuously exerted a force against the contacts in a direction opposed to longitudinal expansion, the desired degree of longitudinal expansion could not always be realized, particularly if the biasing means exerted a force which was difficult to overcome by the expansion force alone. Thus, deformed workpieces or workpieces having undesirable physical characteristics would often be generated.

The present invention contemplates an improvement to resistance type heating apparatus of the type herein-

above described which overcomes all of the above referred problems and others generally associated therewith and provides an improved longitudinal workpiece expansion compensating means which is readily adaptable to present resistance heating apparatus, is adjustable to permit compensation for any length of expansion and provides means which do not interfere with the ordinary workpiece expansion during heating.

In accordance with the present invention, there is provided an improvement used in compensating for longitudinal expansion of an elongated workpiece during heating. The improvement is directed for use in resistance heating apparatus of the type utilizing first and second pairs of heating contacts spaced axially of the

workpiece and where at least one contact of each pair of contacts is movable between a first open condition and a second workpiece clamping and heating condition with the workpiece extending therebetween. The compensating means permits one of the pairs of contacts to move unrestricted away from the other pairs of contacts from a first spaced normal position in a direction generally axial to the workpiece during heating thereof and includes separate means for selectively forcing the one pair of contacts axially back to the first position following heating and return of the one pair of contacts from the second to the first condition.

In accordance with another aspect of the present invention, there is provided a method of resistance heating an elongated workpiece having an axis which comprises the steps of: clamping the workpiece between first and second pairs of electrical contacts at first and second positions respectively; passing electrical current through the contacts; allowing the first pair of contacts to move axially with the workpiece to a third position as the workpiece expands when the current is passed; and, separately moving the first pair of contacts from the third to the first position following heating of the workpiece.

In accordance with another aspect of the invention, the method further includes the step of moving the first and second pairs of contacts from a first opened condition to a second heating and clamping condition at the first position and from the second heating and clamping condition to the first opened condition at the third position. The step of moving the first pair of contacts from the third to the first position occurs at least after the pairs of contacts are moved from the second to the first condition.

The principal object of the present invention is the provision of a workpiece expansion compensator for resistance heating apparatus.

Another object of the present invention is the provision of a workpiece expansion compensator for resistance heating apparatus which presents substantially no resistance to longitudinal expansion of a workpiece during heating.

Still another object of the present invention is the provision of a workpiece expansion compensator for resistance heating apparatus which is adjustable so as to permit use with workpieces of various lengths and experiencing various degrees of longitudinal expansion.

Yet another object of the present invention is the provision of a workpiece expansion compensator for resistance heating apparatus which is readily adaptable to any resistance heating apparatus utilizing spaced contacts to grip a workpiece therebetween during heating.

The invention may take physical form in certain parts and arrangements of parts, a preferred embodiment of which will be described in detail in this specification and illustrated in the accompanying drawings which form a part hereof and wherein:

FIG. 1 is a side view of a resistance heating apparatus which includes the subject invention;

FIG. 2 is a plan view of the apparatus shown in FIG. 1;

FIG. 3 is a cross sectional view taken along lines 3—3 in FIG. 2;

FIG. 4 is a cross sectional view taken along lines 4—4 in FIG. 1; and,

FIG. 5 is an enlarged plan view of the contact arm assemblies in order to show the subject invention in more detail.

Referring now to the drawings wherein the showings are for the purposes of illustrating the preferred embodiment of the invention only and not for purposes of limiting same, the FIGURES show an apparatus having a resistance heating portion A, workpiece supply area B, workpiece feeder system C, workpiece removal system D, electrical supply area E and apparatus framework F.

Specifically, and with particular reference to FIGS. 1, 2 and 5 and resistance heating portion A, it will be seen that it includes a pair of spaced apart contact arm assemblies 10,12 received on an elongated mounting shaft 14 supported by apparatus framework F in any convenient manner. It is to be appreciated that assemblies 10,12 are identical to and oppositely disposed from each other so that description will hereinafter only be made with reference to assembly 10, it being understood that assembly 12 is identical thereto unless otherwise specifically noted. Assembly 10 includes a contact arm assembly hub 16 which comprises that portion of the assembly which is received over mounting shaft 14. The hub is received thereon in a sliding relationship so that assembly 10 may be easily moved longitudinally along the shaft in either direction. Pivotally mounted to the hub by convenient means are contact arms 18,20 which form a scissors-like assembly. A fluid cylinder 22 is operatively disposed between the contact arms at one end thereof to drive the other ends of the arms between an open and closed relationship relative to each other. It will be appreciated that fluid cylinder 22 may be comprised of any type of fluid cylinder, however, in the preferred embodiment, a pneumatic cylinder is employed and standard clevis type mountings are used to affix the cylinder relative to the contact arms. Disposed immediately adjacent contact arms 18,20 on hub 16 are a pair of spur gears 24,26 which intermesh with each other in order to assure unity of movement between arms 18,20 respectively (FIG. 3). Use of these gears is known for providing such unity of movement.

With particular reference to FIGS. 1 and 4, it will be seen that disposed on the opposite ends of contact arms 18,20 from fluid cylinder 22 are contact assemblies 28,30 respectively. This type of contact assembly is known and comprises insulators 32,34 spaced between the contact arms and copper contact blocks 36,38. The contact blocks include V-shaped workpiece receiving grooves 40,42 therein as is also known. Contact assemblies 28,30 may be made self-aligning by pivotally mounting them to arms 16,18 so they will at least pivot through a plane transverse to the plane of the associated contact arm assembly. The self-aligning feature

permits compensation for workpiece run-out to assure the desired workpiece contact is obtained during heating.

To maintain contact arm assemblies 10,12 in the desired spaced apart positions along mounting shaft 14, split-block retainers 50 are used on each side of hubs 16 as is best shown in FIG. 5. Each split block retainer is comprised of block halves 52,54 which are closely received over shaft 14 and tightly drawn thereagainst by means of bolts 56 passing through halves 52 into halves 54. It should be noted that the retainers used with assembly 10 may be permanently affixed to the hub 16 associated therewith and that the retainers employed with assembly 12 are independent of the hub 16 associated therewith. It should further be noted that the retainer 50 associated with the outside end of contact arm assembly 12 includes an elongated block half or compensator base 58 in place of a block half 54. The use of the elongated block half 58 will hereinafter be more fully described.

With particular reference to FIGS. 2, 3 and 5, it will be seen that disposed adjacent hub 16 of contact arm assembly 12 is a longitudinal expansion compensator generally designated 60. More specifically, compensator 60 includes a fluid cylinder 62 conveniently mounted to an end plate 64 of the hub. Cylinder rod 66 of the fluid cylinder has disposed adjacent the end thereof a generally circular pressure plate 68. A fluid passage 70 is employed when it is desired to expand the fluid cylinder in a known manner. The controls necessary to effect selective expansion and retraction of cylinder 62 are also known and therefore not shown. The use of expansion compensator 60 will be hereinafter more fully described relative to operation of the apparatus.

Workpiece supply area B (FIG. 1) is comprised of a workpiece magazine 80 of any convenient type known for handling elongated steel shafts and which, in the preferred embodiment, comprises a gravity feed magazine. As shown, the magazine includes a loading end 82 and a feeding end 84 disposed therebelow. As seen in FIGS. 1 and 2, a plurality of cylindrical steel shafts S are placed in the magazine in a side-by-side relationship. It should be noted that in this embodiment of the invention, all the workpieces are of the same length and of substantially the same diameter. Spaced immediately adjacent feeding end 84 is a shaft receiving head 86 which includes a generally U-shaped channel 88 therein adapted to receiving a single elongated shaft S. A fluid cylinder 90 is disposed therebelow and includes a cylinder rod 92 connected with the head so that in the retracted position of the cylinder, the head is immediately adjacent feeding end 84 to receive a workpiece S and in the extended position, the head is disposed adjacent resistance heating portion A. A head extension 94 is provided to extend between head 86 and cylinder 90 and acts to prevent other workpieces S from leaving the magazine when the head is moved to the extended position.

Workpiece removal system C (FIG. 1) comprises a roller conveyor generally designated 100. Conveyor 100 includes elongated L-shaped channel members 102,104 having a plurality of roller elements 106 extending transversely therebetween. These rollers could be of several types, however, in the preferred embodiment, they comprise steel rollers which include a generally U-shaped necked portion 108 to accommodate

and maintain workpieces S in the desired position as they pass therealong. Conveyor 100 is received on a conveyor stand comprised of a plurality of vertical frame members 110 and any necessary horizontal cross frame members (not shown). Each vertical frame member 110 includes a plurality of conveyor position mounting holes extending longitudinally therealong so that conveyor level mounting pins 112 may be positioned therethrough in order to support the conveyor. An elongated rear baffle 114 and front baffle 116, co-extensive with conveyor 100, provide means whereby workpieces A are guided from resistance heating portion A to the conveyor rolls following heating.

Electrical supply area D is conventional and therefore not shown in detail. It supplies 60 cycle electrical current through the necessary electrical cables to the contact assemblies. At the same time, and also as is conventional, coolant fluid is supplied through coolant supply lines (not shown) to maintain the contact assemblies below their melting temperatures.

Apparatus framework E includes a plurality of tubular vertical frame members, tubular horizontal frame members and tubular angle frame members. It is to be understood that the frame is designed so as to mount the individual component assemblies as hereinabove previously described in the required relative positions. Further, it is possible to include a sheet metal cover around this framework so as to protect the components from destructive elements oftentimes found in industrial environments, to protect workmen coming into contact with the apparatus and to present a single unit package. As the framework itself does not form a part of the present invention, it is not more fully described.

In describing the operation of the subject invention, reference will be made to one workpiece S and to FIGS. 1, 2 and 5. It is first necessary to "set" contact arm assemblies 10,12 in the desired position axially along mounting shaft 14. Depending upon the length of workpieces S to be heated, the contact arm assemblies are positioned so that contact assemblies 28,30 will be spaced immediately adjacent the end points of a workpiece placed in a heating relationship therewith. Once assembly 10 is so positioned, bolts 56 are tightened so as to bring block halves 52,54 of the two split-block retainers 50 into close clamping engagement with the mounting shaft in order to assure retention of the contact arm assembly in that position. The split-block retainer 50 associated with the inside of contact arm assembly 12 is then similarly placed in a clamping relationship with the shaft as hereinabove described. It should be noted again that retainers 50 associated with assembly 10 are affixed to the hub 16 and that retainers 50 associated with assembly 12 may be spaced along shaft 14 independent of the associated assembly. Retainer 50 associated with the outside of hub 16 for assembly 12 is moved to a spaced apart position from the assembly a distance slightly greater than expected axial movement of the hub due to the force created by expansion of a workpiece S during heating. This distance is easily ascertainable from engineering tables or from the results of previously conducted test heatings. With contact arm assembly 10 permanently located and with contact arm assembly 12 disposed against its inner retainer 50, the apparatus is in readiness for heating a workpiece S.

In order to feed a workpiece into a heating position, cylinders 22 are moved to the retracted position in

order that contact assemblies 28,30 are moved to a first or opened condition. In this condition, fluid cylinder 90 is energized so that one workpiece S will be carried in U-shaped channel 88 into proximity with resistance heating portion A. Head extension 94 retains the remainder of the workpieces in the magazine during this extension. When the workpiece is in proximity with the contact assemblies, fluid cylinders 22 are energized to the extended position in order that contact assemblies 28,30 are moved to a second or closed condition with workpiece S clamped therebetween in V-shaped grooves 40,42 respectively. Fluid cylinder 90 may then be retracted in order that another workpiece S will be received in U-shaped channel 88 in readiness for another cycle. With workpiece S clamped between the contact assemblies of contact arm assemblies 10,12 electrical energy may be supplied thereto in a known manner to effect resistance heating of the workpiece. During this heating, and as hereinabove stated, workpiece S will experience a certain amount of longitudinal expansion. In using the subject invention, and with reference to FIG. 5, it will be seen that contact arm assembly 12 is free to move longitudinally away from contact arm assembly 10 along shaft 14. The motive force for this movement is provided by the workpiece S itself as it expands. As shown in FIG. 5, this expansion carries the entire contact arm assembly a distance *a* as shown therein. Once heating is complete, the electrical energy supply may be de-energized, cylinders 22 retracted to move the contact assemblies to the first or opened condition and the heated workpiece S removed by gravity and guided by baffles 114,116 into roller conveyor 100. To assure that the workpiece will be removed from the contact assemblies as they are moved apart from each other, workpiece strippers of a conventional type are employed.

Once the heated workpiece is removed, the longitudinal expansion compensator 60 is energized to axially move contact arm assembly 12 along shaft 14 back to its initial position against the associated inner split-block retainer 50. To do this, cylinder 62 is moved to the extended position so that pressure plate 68 engages the inner surface of block half or compensator base 58. In the preferred embodiment, base 58 includes a hole 120 therethrough to receive the end of cylinder rod 66 in order that pressure plate 68 may be received flush against the inside edge of the base. The force exerted by expanding cylinder 62 with pressure plate 68 acting against base 58 is sufficient to move assembly 12 on its sliding mounting with the associated hub 16 to the initial position with the hub engaging the associated inner retainer 50. At this point, assemblies 10,12 are again spaced apart from each other the desired initial distance so that another workpiece S may be fed from supply area B into proximity with resistance heating portion A as hereinabove previously described.

During at least the feeding period, it is advantageous to maintain cylinder 62 in the expanded position in order that contact arm assembly 12 will be positively retained in its "home" position against the inner retainer. Once cylinders 22 have been energized to move the contact assemblies to the second or closed condition, cylinder 62 may be moved to the retracted position in order that contact arm assembly 12 will be free to move away from contact arm assembly 10 during heating as hereinabove previously described. It should be noted that there is a small space *b* between pressure

plate 68 and base 58 when cylinder 62 is in the retracted position and after assembly 12 has been forced away from assembly 10 during heating. This space assures that the longitudinal expansion compensator 60 will not interfere with the heating process should there be, for some reason, additional expansion realized in a particular workpiece.

The invention has been described with reference to the preferred embodiment. Obviously, modifications and alterations will occur to others upon the reading and understanding of this specification. It is my intention to include all such modifications and alterations insofar as they come within the scope of the appended claims or the equivalents thereof.

Having thus described my invention, I now claim:

1. In a resistance heating apparatus for heating an elongated workpiece having an axis wherein said apparatus includes first and second pairs of heating contacts spaced axially of said workpiece and at least one contact of each pair of contacts being movable between a first opened condition and a second workpiece clamping and heating condition with said workpiece extending therebetween and means for supplying electrical energy to said pairs of contacts for heating said workpiece when said pairs of contacts are in said second condition, the improvement comprising:

compensating means for allowing said first pair of contacts to move unrestricted away from said second pair of contacts from a first spaced normal position in a direction generally axial to said workpiece during heating thereof, said movement being solely caused by longitudinal expansion of said workpiece during said heating and separate means for forcing said first pair of contacts axially back to said first position following heating of said workpiece and return of at least said first pair of contacts from said second condition to said first condition, said force means being selectively energizable between non forcing and forcing conditions.

2. The improvement as defined in claim 1 wherein each contact of said first and second pairs of contacts is received on a mounting shaft, said compensating means including means for allowing said unrestricted movement of each contact of said one pair of contacts longitudinally along their mounting shaft and means for fixedly securing each contact of said second pair of contacts in a direction longitudinally along their mounting shaft.

3. The improvement as defined in claim 2 wherein said forcing means comprises a fluid cylinder disposed in an operative relationship with said first pair of contacts.

4. The improvement as defined in claim 3 wherein said first and second pairs of contacts are disposed on a common mounting shaft, said forcing means further including an adjustable stop received on said shaft adjacent said first pair of contacts for cooperation with said fluid cylinder.

5. The improvement as defined in claim 4 wherein said first pair of contacts are mounted to said mounting shaft by a single contact mounting unit, said fluid cylinder being disposed in said unit and including means for controlling said cylinder for retaining said cylinder in a retracted condition when said unit is moved axially away from said first normal spaced position during heating and for expanding said fluid cylinder to engage 10 said stop in order to force said unit back to said first position when said first and second pair of contacts have been moved to said first condition from said second condition following heating.

6. A method of resistance heating an elongated workpiece having an axis, said method comprising the steps of:

clamping said workpiece between first and second pairs of electrical contacts at first and second positions respectively; passing electrical current through said contacts; allowing said first pair of contacts to move axially unrestricted with said workpiece to a third position as said workpiece longitudinally expands during said step of passing, said expansion providing the only force for moving said first pair of contacts to said third position; unclamping said workpiece from between said first and second pairs of electrical contacts at said third and second positions respectively; and, separately moving said first pair of contacts from said third to said first position following said step of unclamping.

7. The method as defined in claim 6 wherein said step of clamping comprises moving said first and second pairs of contacts from a first opened condition to a second heating and clamping condition at said first and second positions and said step of unclamping comprises moving said first and second pairs of contacts from said second heating and clamping condition to said first opened condition at said third and second positions, said step of moving said first pair of contacts from said third to said first positions occurring at least after said pairs of contacts are moved from said second to said first conditions.

8. The method as defined in claim 7 further including repeating said steps for each workpiece to be heated.

* * * * *
